UNITED STATES PATENT OFFICE

CARL AUGUST GROSSER, OF KILLARNEY, BOGGABRI, NEW SOUTH WALES, AUSTRALIA

AEROPLANE

Application filed June 2, 1931. Serial No. 541,573.

The invention relates to aeronautics and has for its object the provision of means whereby nose diving and rolling of an aeroplane may be prevented.

5 Apparatus according to my invention may be brought into operation by the pilot when for any reason dangerous rolling appears likely to occur or nose diving has occurred or appears imminent. The apparatus may 10 also be used to facilitate landing.

The apparatus comprises a stalk or standard hinged at its lower end to the aeroplane in such manner that it may be turned down until approximately horizontal and in line 15 with the body of the plane, or, may be turned approximately vertical at right angles to the body of the plane.

Upon the end of the stalk, opposite to the hinge, is fixed what I term a stabilizer comprised of air vanes crossing each other at 20 right angles upon a line corresponding to the axis of the stalk and tapering at both ends.

The stalk will under normal conditions lie nearly horizontal with the vanes so disposed 25 that the lower part of the then vertical vane will be received in an opening at the middle of the wing of the aeroplane and the horizontal vane will be parallel with the top of the wing and a little above it.

30 With the vanes so disposed resistance presented to air will be only sufficient to produce a tendency in the stalk to turn upwardly and consequently when a restraining rope is released by the aviator it will assume vertical 35 position.

The rope is led to the drum of a winch by which the stabilizer may be drawn down to and retained in its normal position.

40 There may be two or more sets of stabilizing apparatus, their stalks being arranged in line one behind the other and both or all will be simultaneously controlled from the same source.

45 To impart forward movement to a falling aeroplane when the motor has stalled I employ upon each side of the body an air paddle wheel which is rotated by the upward current of air and imparts motion to an air 50 screw.

I will now describe my invention in detail by reference to the drawing wherein:—

Fig. 1 is a side elevation and

Fig. 2 a corresponding plan.

The stalk 1 is pivoted at 2 upon a standard 55 3 fixed in the aeroplane body 4 and has fixed upon its outer end a stabilizer comprised of the vanes 5 and 6 which cross each other at right angles and converge towards a point 7 at one end and towards a point 8 at the other 60 end.

As shown in dotted lines Fig. 1 the lower part of vane 5 will normally pass into a recess in the middle of the plane wing while the vane 6 will be nearly horizontal and a little 65 above the wing.

The stalk is held down by a rope 9 which passes around guide sheaves 10 and 11 to the barrel 12 of a winch having the usual ratchet wheel 13 and retaining pawl 14. 70

The pawl is adapted to be readily released by the aviator to permit the barrel to rotate and allow the stem to assume vertical position.

Another similar stabilizer 15 is fixed to a 75 stalk 16 pivoted at 17.

A rope 18 connecting stalks 1 and 16 retains the latter stalk in its normal position and serves as a stay when both stalks are vertical. 80

The lower part of the vane 19 of stabilizer 15 normally lies in a recess in the body of the aeroplane.

Rotatably mounted in brackets 20 upon each side of the body is an air paddle wheel 85 21 the paddles being disposed longitudinally to the body.

Upon the axle 22 of the paddle wheel is fixed an air screw 23 which is constructed in the usual manner to impart forward motion to the aeroplane. 90

A curved windshield 24 shields a little more than half of the wheel upon one side of its axis from air current due to the fall of the aeroplane, whereby pressure of air on the paddles of the other part causes the wheel 95 to rotate.

I claim:—

For the purpose specified in combination an aeroplane, rotatable paddle wheels 100

cated one upon each side of the body thereof, the paddles of the wheels longitudinally disposed relatively to the body of the aeroplane, an air shield for some of the paddles and an air screw upon the axle of each paddle wheel as described.

In testimony whereof I have signed my name to this specification.

CARL AUGUST GROSSER.
